(57) **CLAIM**

The ornamental design for an automobile tire, as shown and described.

DESCRIPTION

FIG. 1 is a front view thereof;

FIG. 2 is a rear view thereof;

FIG. 3 is a left side view thereof;

FIG. 4 is a right side view thereof;

FIG. 5 is a top view thereof;

FIG. 6 is a perspective view thereof;

FIG. 7 is an enlarged cross-section view taken along the line 7—7 in FIG. 1; and,

FIG. 8 is an enlarged tread taken along the line B1-B2 in FIG. 1, in the part 8—8 of FIG. 4.

The broken lines illustrate environmental structure and form no part of the claimed design.
